[57] CLAIM

The ornamental design for a model display shelf, as shown and described.

DESCRIPTION

FIG. 1 is a perspective view of the model display shelf. The broken-line disclosure of model cars is for illustrative purposes only and forms no part of the claimed design.

FIG. 2 is a perspective view as seen from the right end thereof;

FIG. 3 is a perspective view seen from the left end thereof;

FIG. 4 is a front view thereof;

FIG. 5 is a rear view thereof;

FIG. 6 is a top view thereof;

FIG. 7 is a bottom view thereof;

FIG. 8 is a view of the left end thereof; and,

FIG. 9 is a view of the right end thereof.
